Primary Examiner — Marianne Pandozzi

(57) **CLAIM**

The ornamental design for an aerator pouring device, as shown and described.

DESCRIPTION

FIG. 1—is a perspective view of the aerator pouring device showing my new design;

FIG. 2—is a top view thereof;

FIG. 3—is a bottom view thereof;

FIG. 4—is a right side view thereof;

FIG. 5—is a left side view thereof;

FIG. 6—is a back side view thereof; and,

FIG. 7—is a front side view thereof.

The broken lines in the drawings is included for the purpose of illustrating environment and forms no part of the claimed design.
